ADJUSTABLE AND REVERSIBLE STUD
REMOVERS AND RESETTERS

George M. Walraven and Raymond G. Knudsen,
Kenosha, Wis., assignors to Snap-On Tools Corporation,
Kenosha, Wis., a corporation of Delaware

Application January 3, 1949, Serial No. 69,008

4 Claims. (Cl. 81—53)

1

This invention relates to adjustable and reversible stud removers and resetters, although certain features thereof may be employed with equal advantage for other purposes.

It contemplates more especially the provision of improved and more effective instrumentalities for gripping various sized studs for effecting the turning thereof in one direction or another so that their removal or resetting is effectively accomplished.

Numerous types of stud removers have heretofore been proposed, but these have not proven entirely satisfactory in all situations involving studs which do not have polygonal heads or nuts to afford the use of a standard wrench or socket to impart rotary movement thereto. Many problems are involved in grasping various sized studs, especially for turning in either direction and to accomplish the grasping thereof without any polygonal head or thread so that standard tools may be utilized.

One object of the present invention is to simplify the construction and improve the operation of devices of the character mentioned.

Another object is to provide an improved stud engaging mechanism that is adjustable to accommodate different sizes of studs to effectively remove or reset them depending upon the requirements of the particular task.

Still another object is to provide improved gear actuated stud engaging jaws which are manually displaceable to accommodate studs of different sizes.

A further object is to provide improved jaw-engaging means that are spring actuated to a predetermined position so that a manual displacement can be effected in one direction or another to effect stud removal or resetting.

A still further object is to provide improved jaw actuators that are compactly arranged within a housing to preset stud-engaging jaws for effectively grasping variously sized studs to selectively impart rotation thereto in either direction for removal or resetting purposes.

Still a further object is to provide spring positioned stud-engaging jaws with manually displaceable means operatively connected therewith to selectively engage studs of any size within a predetermined range.

Other objects and advantages will appear from the following description of an illustrative embodiment of the present invention.

In the drawing:

Figure 1 is a bottom plan view of a device embodying features of the present invention.

2

Figure 2 is a side view and elevation of the stud remover shown in Figure 1.

Figure 3 is a top plan view of the device shown in Figure 2.

5 Figure 4 is a bottom plan view of the stud remover with the housing plate removed to clarify the showing.

Figure 5 is a bottom plan view similar to Figure 4 with all of the gripping and movable elements 10 removed to show the spring tensioning instrumentalities.

Figure 6 is a sectional view through the shanks of the gripping elements and showing the gear actuated instrumentalities for displacing the jaws, 15 viewed substantially along line VI—VI of Figure 8.

Figure 7 is a bottom plan view of a device similar to Figure 4 with the jaws displaced to a position engageable with a stud for imparting rotation thereto in a clockwise direction (viewed 20 from Figure 7) and taken substantially along line VII—VII in Figure 8.

Figure 8 is a sectional view in elevation taken substantially along line VIII—VIII of Figure 1.

Figure 9 is a top plan view of a stud-gripping 25 jaw shown assembled in Figures 4 and 7.

Figure 10 is a side view in elevation of the jaw shown in Figure 9.

The structure selected for illustration is not intended to serve as a limitation upon the scope or teachings of the invention, but is merely illustrative thereof. There may be considerable variations and adaptations of all or part of the teachings depending upon the dictates of commercial practice.

35 The present embodiment comprises a substantially cylindrical housing 10 which merges with an inwardly curved hood or enclosure 11 that in turn connects with an elongated cylindrical shank 12. The housing 10, hood 11, and shank 12 are formed integral to comprise a unitary structure that terminates in a polygonal extremity such as a hexagon 13 which is adapted to be engaged by a wrench or wrench socket to impart rotation to the housing structure in either direction after a 40 stud has been gripped for removal or resetting as will appear more fully hereinafter.

45 The interior cylindrical chamber 14 of the housing 10 communicates with an annular shoulder 15 that, in turn, communicates with an axial elongated bore 16 provided in the elongated housing shank 12 to extend entirely therethrough to accommodate a stud which may be disposed therein for gripping as will appear more fully hereinafter. The annular shoulder 15 receives a 50 collar 17 which is rotatively mounted therein to

serve as a complement thereof. The collar 17 is provided with diametrically opposed angular notches 18-19 which are defined by converging walls that cooperate with an elongated detent 20 that is reciprocally mounted in an aperture or bore 21 extending radially through the hood portion 11 of the housing 10 in alignment with the internal annular shoulder 15 to engage the annular notch 18 or 19, depending upon the position of insertion of the collar 17.

A spring 22 is disposed in the aperture or bore 21 behind the detent 20 to normally urge the latter in engagement with the angular notch 18 or 19. As shown, the radial aperture 21 communicates with an enlarged orifice which is intended to receive a closure cap against which the spring 22 abuts. A jaw positioning or displacing ring or band 24 is mounted in an annular groove 25 provided on the periphery on the hood portion 11 of the housing 10 in line with the spring detent receiving aperture or bore 21 retaining the spring retaining closure cap 23 in assembled position and to actuate the stud-engaging jaws or grippers as will appear more fully hereinafter. The external ring or band 24 is retained in the annular groove 25 by means of a split retainer wire ring 26 which rests in a correspondingly sized and shaped groove 27 to rotatively retain the external actuator ring or band 24 in assembled position against removal from the annular groove 25. To enable the convenient manual rotary displacement of the band 24, the exposed surface thereof is knurled as at 28 (Figure 2) so that an effective finger grasp thereof will result in its rotation in either direction to position the stud engaging jaws or grippers to be hereinafter described.

It is to be noted that the collar 17 has a reduced shoulder 29 extending in the housing chamber 14 to receive a ring gear 30 for rotation thereon. The ring gear 30 has a radially extending arm 31 formed thereon to project through an arcuate slot 32 (Figure 7) in the housing 10 to engage in a notch 33 provided in the knurled ring 24 so that rotation of the latter will cause corresponding rotation in either direction of the gear ring 30 within the limits of the arcuate housing slot 32 so that gear ring 30 will rotate with the collar 17. It is to be noted that the collar 17 is provided with tangential parallel portions 34-35 in the shoulder 29 thereof to receive the correspondingly shaped and complementary axial bore of the ring gear 30 which will rotate the collar 17 therewith responsive to manual rotary movement imparted to the band 24. Consequently, the ring gear 30 will be spring impelled by the detent 20 to normally assume a predetermined position as the spring urged detent exerts a camming action on either of the angular walls of the collar notches 18 or 19.

The gear ring 30 has gear teeth 36 provided equidistantly thereon in a plurality of sectors, in this instance three symmetrically disposed at 120° angular sectors, to mesh with a corresponding number of gear sectors 37. The gear sectors 37, in this instance three, that are each provided with polygonal apertures 38 to fit over correspondingly shaped shoulders 39 (Figure 10) on the ends of the shank portions 40 of a plurality of stud engaging jaws or grippers 41, in this instance three in number. The stud engaging jaws 41 are substantially arrow-shaped and have oppositely extending and converging jaw surfaces 42-43 that meet along a median line 44.

thereof to engage a threaded stud 45 of the type usually found in engine block heads. The jaws or grippers 41 engage the studs 45 on one or the other of the converging engaging surfaces 42-43 thereof. The converging engaging surfaces 42-43 are slightly convex to effectively grasp the cylindrical wall of the stud 45 depending on the direction of rotation to be imparted thereto. To render the engagement between the jaw engaging surfaces 42-43 and the smooth cylindrical wall of the stud 45 more effective and insure against slippage, the slightly convex jaw engaging surfaces 42-43 are provided with transverse teeth or serrations 45-46, respectively.

The jaw shanks 40 are provided with apertures or bores 47 therethrough for pivotal mounting on screw fasteners 48 threaded at their extremities 49 to engage correspondingly threaded apertures 50 provided in the hood portion 11 of the housing 10. The screw fasteners 48, in this instance three, not only serve as pivotal mounts for the jaws or grippers 41, but also serve to retain a cover plate 51 in position for support on an annular shoulder 52 provided in the housing 10 in communication with the open end 53 thereof. The cover plate 51 has a central or axial opening 54 which is sized to receive the maximum diameter of a stud 45 that can be effectively grasped with the jaws or grippers 41 from the smallest size to the largest determined by the range for which the instrumentalities are designed.

With this arrangement, the gear sectors 37 are actuated by the gear ring 30 pivotally to displace the stud engaging jaws or grippers 31 in either direction from their initial closed radial position. This is effected responsive to the rotation of the ring or band 24 for opening the jaws 41 to a position that will accommodate a particular sized stud 45 that is disposed through the central opening 54 in the housing cover plate 51.

It should be noted that the spring impelled detent 20 will normally urge the jaws or grippers 41 to their true radial position as illustrated in Figure 4 so that manual displacement of the ring or band 24 in one direction or the other will displace the jaws or grippers 41 outwardly on one side or the other of the stud 45 and offset from the initial radial jaw position which are the lines from the center of the stud 45 to the centers or axes of the threaded jaw mounts 48, the direction of pivotal displacement being determined by the direction in which the stud 45 is to be turned.

After the ring or band 24 has been rotated to spread the jaws or grippers 41 and the stud 45 has been engaged by releasing the actuating ring or band 24 so the jaws or grippers 41 will be spring urged in contact with the stud 45, a wrench or wrench socket is applied to the polygonal extremity 13 of the housing shank 12 to forcefully remove or reset the stud 45 depending upon the requirements of any particular task. It will be apparent from the foregoing description that a very effective grasp and turning movement may be imparted to studs 45 owing to the improved and simplified operating instrumentality described and illustrated in the preferred embodiment of the present invention. Obviously, a change in proportion and size of the instrumentality will enable even larger studs to be removed or reset than illustrated, and nothing herein shall be construed as a limitation thereon.

While we have illustrated and described a preferred embodiment of this invention, it must be understood that the invention is capable of considerable variation and modification without departing from the spirit of the invention. We, therefore, do not wish to be limited to the precise details of construction set forth, but desire to avail ourselves of such variations and modifications as come within the scope of the appended claims.

We claim:

1. In a stud remover and resetter, the combination with a housing having an opening therein to receive a stud for gripping engagement, of a plurality of stud engaging grippers movably mounted in said housing for displacement along an arc substantially intersected by the common housing opening and gripper radii, an external ring rotatively mounted on said housing, gripper actuating means including intermeshing gear teeth elements operatively connected with said external ring for shifting said grippers to one or the other side of said gripper radii to receive a stud for gripping on one or the other side thereof for removal or resetting purposes, and means for normally urging said grippers to assume an initial inoperative position in alignment with said common radii.

2. In a device of the character mentioned, the combination with a housing adapted to freely receive an elongated stud therein, of a plurality of stud grippers pivotally mounted in said housing, said grippers having opposite engaging surfaces for selective directional displacement in the path of a stud disposed in said housing, gear segments detachably associated with said grippers for rotation therewith, a gear ring journaled in said housing within the radius of said gripper mountings for meshing engagement with said gear segments, an external actuator on said housing operatively connected to said gear ring, and spring means for normally urging said gear ring to assume an initial position in conjunction with said grippers.

3. In a device of the character mentioned, the combination with a housing adapted to freely receive an elongated stud therein, a plurality of stud grippers movably mounted in said housing for displacement in the path of a stud received there-

in, circular means journaled in said housing for free rotation therein, spring means for normally retaining said circular means in an initial position against rotary displacement in either direction, complemental means interposed between said circular means and grippers for displacing the latter against the normal urge of said spring means, and means on said housing for enabling the rotation thereof to turn a stud held fast by said grippers.

4. In a device of the character mentioned, the combination with a housing adapted to freely receive an elongated stud therein, a plurality of stud grippers movably mounted in said housing for displacement in the path of a stud received therein, circular means journaled in said housing for free rotation therein, there being an angular notch in said circular means, spring impelled detent means coacting with said angular notch for normally retaining said circular means in an initial position against rotary displacement in either direction, complemental means interposed between said circular means and grippers, and an external actuator associated with said housing to operate said complemental means for displacing the latter against the normal urge of said spring means.
